UNITED STATES PATENT OFFICE.

FRANK HENRY DUTTON, OF JOHANNESBURG, TRANSVAAL, SOUTH AFRICA,
ASSIGNOR TO ROADRAILS, LIMITED, OF LONDON, ENGLAND.

LOCOMOTIVE FOR LIGHT RAILWAYS.

1,416,625.

Specification of Letters Patent. Patented May 16, 1922.

Application filed August 22, 1921. Serial No. 494,181.

To all whom it may concern:

Be it known that I, FRANK HENRY DUTTON, a subject of the King of Great Britain and Ireland, residing 183 South African

5 Railway Building, Johannesburg, Transvaal, Union of South Africa, have invented certain new and useful Improvements in Locomotives for Light Railways, of which the following is a specification.

10 This invention has for its object to effect improvements in the existing light railway systems and more particularly concerns an improvement in the locomotive or driving arrangements used in connection therewith.

15 It is known to use a driving arrangement according to which the drive is derived from the road whilst the load is carried on the rails and in such arrangements it has hitherto been customary to have the driving wheels

20 on the locomotive running on special roadways or prepared tracks, laterally of or inside the actual rails as has for instance been described in the specification of my United States Patent No. 1306051, granted June 10, 25 1919.

Now according to this invention instead of pivoting each bogie to the locomotive frame at one central point thereof, as hitherto, each bogie is connected with the locomotive frame laterally on both sides by self-steering connections. The frame of the locomotive is made preferably in two sections which are pivoted, hinged or articulated at any convenient point centrally with the road 30 or driving wheels preferably, however, as far as possible below the axle thereof. The axle on which the driving or road wheels rotate has its trunnions journaled in bearings provided with lateral guide brackets 35 and supporting a spring or like cushioning or shock absorbing device of which appropriate parts or extension on the main frame sections constitute a cooperative part.

40 The road driving wheels are driven preferably through a chain gear from a differentially driven countershaft as in the patent above referred to.

45 The accompanying drawings illustrate by way of example a form of construction embodying the invention.

Figure 1 is a side elevation and

50 Figure 2 a plan view of a light railway vehicle having its frame mounted on two bogies, one in front (on the right) and one 55 in rear of the driving wheels.

Figure 3 is a vertical cross section through the axle of the driving wheels.

Figure 4 a perspective view of the road or driving wheels and adjacent parts showing particularly the hinging of the fore and aft members of the longitudinal frame bearers and the manner of suspending and cushioning them on the road wheel axle.

Figure 5 is an end elevation, and

Figure 6 a perspective view of a bogie 65 showing the self-steering connection of such bogie to the locomotive frame while.

Figure 7 shows in a plan view of a bogie, showing the action of the self-steering connection.

Figure 8 shows in a section along the road wheel axle a modification to illustrate how four driving wheels, two inside and two outside of the rail track, may be arranged on the said axle if desired.

70 In the construction shown the main frame of the vehicle consists of longitudinal side members or bearers each divided into two parts A, B and A', B' respectively, each bearer extending fore and aft from the axle 80 C of the road or driving wheels D which as shown are centrally disposed and arranged to run inside between the rails of the track. The two bearers are arranged in an identical manner, that is to say the 85 complementary sections of each bearer are connected one with the other on each side below the axle C by means of a hinge pin E and are suspended by means of vertical arms A², B², which by preference are made 90 integral with the corresponding bearer sections.

75 As shown these arms A², B², on each side form a strap suspension each arm rising from its bearer section and terminating in 95 a hook, the hooks of the straps on each side facing each other and resting on a compression spring F which is supported on the corresponding axle end C by means of the axle bearing G on that side as shown clearly 100 in Figure 4. These bearings G are each provided with prong-shaped lugs g arranged laterally opposite each other and adapted to embrace and form a guide for the arms A² and B² so that a yielding connection is 105 formed on each side between the axle C and the frame enabling the straps A² and B² to slide up and down between the guides g, when variations in the level of the road or obstacles are encountered and the axle C 110

to assume its requisite position relative to the main frame.

The driving wheels D, preferably shod with solid rubber tyres, are loosely journaled on the axle C. They are provided with sprocket wheels D² mounted on their hubs and driven by chains D' from a countershaft H differently driven from the engine J by a chain J' or like driving transmission; and appropriate differential gearing housed in the gear box H' being used to establish connection between the chain sprocket wheels employed for this purpose.

The longitudinal bearer sections A, B, 15 and A', B' respectively are each raised and rectangularly offset at their outer ends where they are supported by king pins on the respective bogie K by the interposition at each end of a self-steering mechanism of identical construction.

This mechanism as described in connection with the forward bogie (on the right hand side) comprises the following parts, shown more clearly in Figures 5, 6 and 7.

25 Rigidly secured to the under side and projecting downwardly from the bearer sections A and A' respectively are king pins a, a' each constituting a fulcrum for a bell crank lever L, l and L', l' respectively. 30 These bell crank levers are mounted symmetrically on their pins so that normally the arms L and L' pointing downwardly stand at right angles to the vehicle frame. The arms L, L' by means of pin-shaped extensions m, m' engage slots k, k' arranged in alignment near the outer ends of the cross beam K' and in line with the wheels of the bogie whilst the arms l, l' of the said bell crank levers are linked up by a connecting rod M. From the inspection of Figures 2 and 7, it will be seen that any deviation of the track from the straight—that is to say when the bogie of the locomotive frame deviates from parallel positions on a curve—will 40 cause the cross beam K' of the bogie to take up a position coinciding with the radius of that curvature. This results from the action of the cross beam K' on the pins m, m' of the bell crank arms L, L' which are caused by the connecting rod M to co-operate and to swing out for an equal amount, but on account of the symmetrical arrangement in opposite directions thus effectively steering the bogie without disturbing the distribution of 50 the load on the wheels on either side of the bogie.

Figure 8 illustrates by way of example a modification in which use is made of four driving wheels all arranged on one and the 60 same axle C, two to run inside and two outside the rail track. These four wheels may be driven separately from the same counter-shaft H or they may be driven in pairs and if desired the outer wheels and the inner 65 wheels may be arranged on different axles.

The longitudinal bearer sections B, B' are supported on the rear bogie by means of the same arrangement as already stated.

With the aid of an arrangement as above described the stability of the vehicle is ensured by eliminating the centrally pivoted bogie as usually constructed and providing in its place a bogie whereby complete support for the frame is obtained in line with the bearings or wheels of the bogie. The 70 articulation referred to ensures that the weight of the locomotive is distributed as desired either upon the driving wheels or upon the rail bogies, and further ensures when running over uneven ground that the 80 load carried by each respective axle, whether bogie or driving wheels, remains the same.

It is obvious that with an arrangement on the above principle, and where in fact a bogie is used fore and aft, the locomotive 85 would be readily reversible. It will be seen that in other respects also the invention admits of numerous constructional modifications by those skilled in the art without departing from the main spirit thereof, and therefore should not be deemed to be strictly limited to the specific arrangement or to the configuration of their details hereinbefore particularly described.

I claim:

1. In a light railway vehicle in combination, a bogie, a frame supported on said bogie and self steering connections between the said frame and said bogie substantially as set forth.

2. In a light railway vehicle in combination, a bogie, a frame supported at one end on said bogie, a bogie supporting the opposite end of said frame and self-steering connections between each bogie and the respective end of said frame substantially as set forth.

3. In a light railway vehicle in combination, a bogie, a pair of road driving wheels and a frame supported on the said bogie 110 and hinged centrally with the said road driving wheels substantially as set forth.

4. In a light railway vehicle in combination, a bogie, a pair of road driving wheels and a frame supported at one end on the said 115 bogie and pivoted on hinge pins on either side centrally with and below the axle of the said road driving wheels substantially as set forth.

5. In a light railway vehicle in combination, a pair of road driving wheels running inside a rail track, a frame supported centrally on the said road driving wheels, a bogie supporting one end of the said frame and self-steering connections between the 125 said bogie and said frame substantially as set forth.

6. In a light railway vehicle a pair of road driving wheels running inside a rail track, a frame hinged centrally with the said road 130

driving wheels, a bogie at each end of said frame and self-steering connections between each bogie and the end of said frame, substantially as set forth.

5 7. In a light railway vehicle in combination, a pair of road driving wheels, a frame pivoted centrally with the said road driving wheels, and a cushioning device between said frame and said wheels substantially as set forth.

10 8. In a light railway vehicle in combination, a pair of road driving wheels, a frame pivoted centrally with and below the axle of the said road driving wheels on each side 15 thereof, a bogie supporting each end of said frame and connected thereto by self steering connections and a cushioning device between the said axle and the said frame on each side thereof substantially as set forth.

20 9. In a light railway vehicle in combination, a pair of road driving wheels, a frame composed of sections hinged together on pins centrally with and below the axle of said driving wheels, a cushioning device on each 25 end of said axle and brackets rising from the hinged sections to form part of the cushioning device and guided by lugs on the latter, substantially as set forth.

30 10. In a light railway vehicle in combination, a bogie, a frame having its end sup-

ported on the said bogie, a lever connection laterally on each side between the said bogie and said frame and a link gear between the said lever connections, substantially as and for the purpose set forth.

35 11. In a light railway vehicle in combination, a pair of road driving wheels, running inside a rail track, a frame centrally hinged with the said road driving wheels on each side thereof and a pair of road driving 40 wheels on the same axle and running outside the rail track, substantially as set forth.

12. In a light railway vehicle in combination, a pair of road driving wheels running centrally within a rail track, a frame centrally hinged with and below the axle of 45 said road driving wheels and spring cushioned thereon on each side, rectangularly raised ends on the frame each supported on a rail bogie and self-steering connections 50 laterally between each end of said frame and its bogie, all substantially as described and shown.

In testimony whereof I affix my signature in presence of two witnesses.

FRANK HENRY DUTTON.
